UNITED STATES PATENT OFFICE.

LEO N. LAREAU, OF PAWTUCKET, RHODE ISLAND, AND OMER J. RAINVILLE, OF SOUTH ATTLEBORO, MASSACHUSETTS.

BOWLING-ALLEY-RESURFACING DEVICE.

1,378,473.

Specification of Letters Patent. Patented May 17, 1921.

Application filed June 7, 1920. Serial No. 386,984.

To all whom it may concern:

Be it known that we, LEO N. LAREAU, a citizen of the United States, residing at Pawtucket, in the county of Providence and 5 State of Rhode Island, and OMER J. RAINVILLE, of South Attleboro, in the county of Bristol and State of Massachusetts, have invented new and useful Improvements in Bowling-Alley-Resurfacing Devices, of 10 which the following is a specification.

This invention relates to certain new and useful improvements in bowling alley resurfacing devices, and the primary object of the invention is to provide a device in which 15 the abrading means is automatically moved step by step along the length of the alley during and simultaneously with reciprocation thereof and further by bodily movement of the device on the alley.

20 The invention further aims to provide a prime mover which effects both longitudinal and reciprocating movement of the abrading element or means.

The invention still further aims to provide 25 a device of the type set forth which may be easily operated, and one of simple and economical construction, and further aims to provide a novel type of adjustment for abrading element so as to vary the pressure of the latter on the surface of the alley.

In the drawings:

Figure 1 is a perspective view of the invention and Fig. 2, is a fragmentary detail end elevation of the frame actuating means.

35 The invention embodies a frame including a pair of curved members 1 between which a vertical lever 2 is pivoted at 3. Cross bars 4 are secured to the end portions of the members 1, and maintain the latter 40 in spaced relation as shown in the drawing. A seat 5 for the operator is suitably secured to the members 1. A pair of rods 6 are connected at their ends to the bars 4 and slidably support a head 7 formed with an opening through which the lower end of the lever 2 freely passes. Anti-friction rollers 8 are carried by the head 7 and are for engagement with the opposite sides of the lower end of lever 2, so that when the lever 50 is operated the head 7 will be reciprocated along the rods 6. Buffers in the form of coil springs 9 are mounted on the ends of the rods 6 so as to cushion the movement of the head 7 upon reciprocation of the latter. A

pair of shafts 10 are carried by the lower 55 ends of the members 1 and have rollers 11 mounted thereon, the rollers being flanged at 12 so as to engage the inner sides of the gutters, thereby to prevent movement of the frame transversely of the alley. The rollers 10 rotate on the alley and two of same have gear teeth 13 formed on their flanges 12, the teeth 13 being engaged with reversible dogs or pawls 14 which are pivoted on levers 15, the latter in turn being pivoted to the 65 adjacent shaft 10. Levers 15 are connected by links 16 to double-crank 17, which latter are journaled on the cross-bars 4 and are further connected by links 18 to the lever 2 as indicated at 19.

A platen 20 is provided with clips or clamps 21 which latter hold the sand paper 22 in position against the lower face of platen 20.

For the purpose of holding the platen 75 with the sandpaper thereon against the surface of the bowling alley which is to be dressed or finished, spring rods 23 are employed which latter are affixed at their upper ends to the head 7 and cross each other and 80 are secured at 24 to the platen 20, from which points 24 the rods are bent upwardly and secured to bars 25 which latter extend transversely of the platen and are adjusted vertically by means of screws and thumb 85 nuts 26. The platen further has the lower ends of vertical rods 27 affixed thereto, the upper ends of the rods passing through the head 7 and having cam members 28 pivoted thereto, so that when both of the cam-members 90 are in the position shown by the one to the right of the drawing, the platen 20 will be raised up out of engagement with the surface of the alley, and when the cam-members are in a position shown to 95 the left of the figure the platen will be lowered to engage with the alley surface.

In operation, lever 2 is oscillated, which causes reciprocation of the head 7 or the rods 6, and at the same time effects reciprocation of the links 18, the latter in turn rocking the double cranks 17, and through the links 16 and levers 15 effecting step by step rotation of the rollers 11, by virtue of the dogs 14 engaging the gear-teeth 13. In 100 order to vary the pressure of the sand paper on the surface of the alley, the thumb-nuts 26 are adjusted up or down so as to cause 105

the lower ends of the rods 23 to bear with greater or less pressure on the platen.

From the foregoing it will be apparent that the device provides a reciprocating movement of the sand paper transversely of the alley, and simultaneously a step by step movement in a selective direction lengthwise of the alley, the latter movement determined by proper setting of the pawls or dogs 14. 10 The device also moves lengthwise of the alley by moving or riding thereon, the alley thus being utilized as a track.

Having thus described our invention, what we claim as new and desire to secure 15 by Letters Patent is:—

1. In a bowling alley resurfacer, a frame composed of two curved members spaced apart at their ends, cross bars connected to said spaced ends, rods connected to the cross 20 bars, a head slidably carried by the rods, a sand paper bearing platen carried by the head, said head having a slot and opposite anti-friction rollers adjacent the ends of the slot, a lever pivoted to the frame and having 25 its lower end extending through the slot and engaging with the rollers, rollers journaled in the frame ends and having flanges abutting the inner sides of the gutters, gear teeth on certain of the flanges, pivoted levers 30 carried by the frame and having pawls engaging the gear-teeth, double cranks journaled on the cross bars, links connecting the levers with the double cranks, and links connecting the double cranks with the first 35 named lever.

2. In a bowling alley resurfacer, a frame, a head reciprocable on the frame, a vertical lever pivoted to the frame and connected to the head for reciprocating same, rollers 40 mounted on the frame and engaging the alley, and means operated by the lever for progressively actuating the frame by and upon each oscillation of the lever.

3. In a bowling alley resurfacer, a frame, 45 a head reciprocating on the frame, means to reciprocate the head, means to progressively move the frame step by step lengthwise of the alley, and means to actuate the last named means by and through said means to reciprocate the head.

4. In a bowling alley resurfacer, a frame, a reciprocating head carried by the frame, a platen, rods connected to the head and to the platen, means to raise and lower the rods 55 and thereby the platen relative to the head, spring devices between the head and the platen to vary the pressure of the platen on the alley, and means to adjust said devices.

5. In a bowling alley resurfacer, a frame, 60 a head carried by the frame, a platen, spring rods secured at their upper ends to the head and having cross-bars secured to their lower ends, said spring rods being bent adjacent their lower end and secured to the platen, 65 and means to raise and lower the cross bars

relative to the platen to thereby vary the action of the spring rods on the platen.

6. In a bowling alley resurfacer, a frame, flanged rollers carried by the frame and having the flanges thereof formed to engage the inner sides of the gutters, and a sandpaper bearing device movably mounted on the frame. 70

7. In a bowling alley resurfacer, a frame, rollers carried by the frame, double cranks carried by the frame, gear-teeth associated with certain of the rollers, levers pivoted to the frame and having pawls engaging the gear-teeth, means connecting the levers with the double cranks, a prime mover, means 80 connecting the prime mover with the double cranks, and a sand-paper bearing member movably mounted on the frame.

8. In a bowling alley resurfacer, a frame, rollers carried by the frame, and having 85 gear-teeth associated with certain of the rollers, a lever pivoted to the frame, means connected to the lever and engaged with the gear teeth to effect step by step rotation thereof upon oscillation of the lever and an 90 abrasive member movably mounted on the frame.

9. In a bowling alley resurfacer, a frame, means to progressively move the frame step by step lengthwise of the alley, a sand-paper 95 bearing member, a prime mover, means to actuate said member from the mover, and means to actuate said frame moving means from the member.

10. In combination with a sand paper bearing member and a frame carrying same, means to actuate the member, and means to move the frame step by step connected to said actuating means. 100

11. In a bowling alley resurfacer, a frame, 105 a movable head carried by the frame, an abrasive carrying platen, means to raise and lower the platen relative to the head, and means for effecting constant tension upon the platen. 110

12. In a bowling alley resurfacer, a frame, a movable head carried by the frame, an abrasive carrying platen, means to raise and lower the platen relative to the head, spring means to hold the platen against the 115 alley under tension, and means to effect adjustment of the spring means.

13. In a bowling alley resurfacer, a frame, traction means for the frame to allow the latter to move longitudinally of the alley, 120 abrasive means, means to mount the abrasive means to allow same to move across the alley and at right angles to the path of travel of the frame, actuating means for the abrasive means, and means operated by the 125 actuating means for actuating the frame.

14. In a bowling alley resurfacer, a frame, traction means for the frame to allow the latter to move longitudinally of the alley, abrasive means, means to mount the abrasive 130

means to allow same to move across the alley and at right angles to the path of travel of the frame, actuating means for the abrasive means, and means operated by the actuating means for actuating the frame step-by-step upon each movement of the abrasive means across the alley.

5 In testimony whereof we have signed our

names to this specification in the presence of two subscribing witnesses.
